UNITED STATES PATENT OFFICE.

GEORGE L. PIERCE, OF NEW YORK, N. Y.

BODY-PROTECTOR.

No. 833,546.

Specification of Letters Patent.

Patented Oct. 16, 1906.

Application filed March 7, 1906. Serial No. 304,703.

To all whom it may concern:

Be it known that I, GEORGE L. PIERCE, a citizen of the United States, residing in the borough of Brooklyn, in the county of Kings, 5 in the city and State of New York, have invented certain new and useful Improvements in Body-Protectors, of which the following is a specification.

This invention relates to devices such as 10 are used by athletes, and particularly those who play games of a somewhat rough character—such as cricket, foot-ball, lacrosse, hockey, base-ball, and the like; and the object of the invention is to provide a simple, 15 light, and relatively inexpensive device which will protect the wearer against blows received in the game.

As herein shown, the invention is embodied in what is commonly called a "shin-guard" 20 to protect the leg between the ankle and knee, but the principle of the invention may as well be embodied in guards or protectors for other parts of the body.

In the accompanying drawings, which 25 serve to illustrate one embodiment of the invention, Figure 1 is a front elevation of the device. Fig. 2 is a rear elevation or inside view thereof. Fig. 3 is an end view or plan of the device. Fig. 4 shows a slightly different construction, which will be hereinafter described.

In the shin-guard shown, 1 designates a base-piece of some strong flexible fabric, which may be leather, cut to the desired or 35 proper shape. This part is adapted to fit closely to the leg or other part of the person to be specially protected. On the outer face of the base-piece 1 is mounted a guard-piece 2, which will be of some light, resilient, and 40 strong sheet fabric, as indurated fiber material, for example. This part 2 is of concavo-convex form and rests only at its lateral edges on the base-piece 1, thus leaving a hollow or space between the two, as seen 45 clearly in Fig. 3. The guard-piece 2, which is to receive the blow, is secured to the base-piece by means of straps 3 3, which are passed through slits 4 in the guard-piece 2 and slits 5 in the base-piece 1. Preferably 50 for the sake of economy and convenience the straps 3 3 are provided each with a buckle 6 and serve as the straps for securing the guard in place on the leg. This double use of the straps, however, is not absolutely es- 55 sential.

In Fig. 4 a construction is shown where the

guard-piece 2 is represented as secured to the base-piece by other means than the straps used for fastening the guard to the leg. In this figure the last-named straps 7 are secured 60 by suitable means to the base-piece, and the guard-piece is secured to the base-piece in a yielding manner by thongs 8, which pass through holes or slots in the parts.

It will be noted that the guard illustrated 65 and described has certain characteristics—namely, the flexible base-piece 1 is relatively broad, and the guard-piece 2 is narrower, so that a considerable margin of the base-piece extends laterally beyond the guard-piece at 70 each side. Also the lateral edges of the guard-piece, which rest upon the outer face of the base-piece, are loosely connected with the latter, so that when a blow is received by the guard-piece, tending to flatten it a little, 75 it is free to expand laterally independently of the base-piece.

When the guard or protector is in place, a blow on the arched guard-piece will not be felt injuriously by the wearer, as the blow 80 tends to flatten the guard-piece, and there is no direct transmission of the force of the blow, owing to the air-space between the parts 1 and 2.

For ventilation the base-piece has in it 85 holes or perforations 9.

Having thus described my invention, I claim—

1. A device for the purpose specified, consisting of a relatively broad base-piece of 90 strong, flexible material, an elongated, upright, concavo-convex guard-piece made from strong resilient material and considerably narrower than the base-piece, said guard-piece resting and bearing loosely at its lateral 95 edges on the outer face of the base-piece and movable thereover, flexible means for holding the guard-piece loosely in place on the base-piece, and means for securing the base-piece to the body. 100

2. A device for the purpose specified, consisting of a base-piece of strong, flexible material, a concavo-convex guard-piece, made from strong, resilient material and considerably narrower than the base-piece, said guard-piece having in it slits and being applied to the middle part of the base-piece with its convex face outward, and straps for securing the device to the body of the wearer, said straps engaging the slits in the guard-piece. 105

3. A device for the purpose specified, consisting of a base-piece of strong, flexible ma-

- 5 terial, a guard-piece 2, of light, strong, re-
silient sheet material, having a set concave
shape, applied to the outer face of the base-
piece, and securing - straps 3, which are
threaded through slits in the respective base-
piece and guard-piece, said straps serving to
secure the two pieces together and also serv-
ing as means for securing the device to the
body of the wearer.
- 10 4. A device for the purpose specified, con-
sisting of a base-piece 1, of strong, flexible
material provided with a plurality of venti-
lating-apertures, a guard-piece 2, of light,
strong, resilient sheet material, having a set

concave shape, applied to the outer face of 15
the base-piece, and securing-straps 3, which
are threaded through slits in the respective
base-piece and guard-piece, said straps serv-
ing to secure the two pieces together and also
serving as means for securing the device to 20
the body of the wearer.

In witness whereof I have hereunto signed
my name, this 5th day of March, 1906, in the
presence of two subscribing witnesses.

GEORGE L. PIERCE.
